(57) **CLAIM**

The ornamental design for a package with anatomically correct product placement window, as shown and described.

DESCRIPTION

FIG. 1 is a front view of a package with anatomically correct product placement window showing my new design, the opposite rear view being unornamented; and,

FIG. 2 is an enlarged sectional view thereof, taken along line 2—2 of FIG. 1.

The broken lines shown in the drawing illustrate portions of the package with anatomically correct product placement window and form no part of the claimed design.
